UNITED STATES PATENT OFFICE.

MARY EDITH WHEELER, OF EVANSTON, ILLINOIS.

WINDOW-CURTAIN PROTECTOR.

Application filed January 23, 1924. Serial No. 687,911.

My invention contemplates a window curtain protector, the purpose of which is to hold the curtain aside and against destructive flapping and shield it from becoming wet or soiled when the window is open.

Broadly, my invention comprises a sleeve, preferably of waterproof material, which is adapted to envelope that portion of the curtain in the zone of window opening. More specifically, I provide such a sleeve which may be opened to receive the curtain, in a loosely gathered condition, which may be attached to the vertical member of the window frame to hold the curtain aside, and which may be rolled up and hidden from view when not in use.

My invention is illustrated in the accompanying drawing, in which,

Fig. 1 is an elevational view showing a curtained window with the device of my invention applied thereto;

Fig. 2 shows the device of my invention as rolled up; and

Fig. 3 shows the device of my invention opened up, exposing the interior thereof.

Referring first to Fig. 3, it will be seen that the device of my invention is formed of a rectangular piece of material 4, which is preferably flexible and waterproof, such as oil-cloth. Its edges are hemmed, as at 5, with the waterproof surface on the outside.

At the top, near each side, an eyelet 6 is provided and near the bottom, at the sides, the respective male and female members, 7 and 7^a, of a clasp are secured.

When the piece 4 is folded over upon itself, with the waterproof surface on the outside, the eyelets 6, 6 come into register, and the clasp 7, 7^a is closed together, forming a sleeve, as shown at the left in Fig. 1. As there illustrated, the hanging curtain has been gathered together, loosely so as not to form creases, and the piece 4 has been folded about it, the registering eyelets 6 being hung upon a hook 8, on the vertical member 9 of the window frame, at a point above a proposed window opening, thus simultaneously supporting the protector and holding the upper corners thereof together, and the clasp 7, 7^a being closed to hold the lower corners together. Thus the curtain is held to the side, and, in the zone of the window opening, between the lower member 10 of the sash and the sill 11, is effectively pro-

tected against rain, snow, dust or soot which might enter, the protector having a generous margin both above and below the opening. The curtain is also protected against flapping due to wind or draft passing through the window opening, which is so destructive particularly in the case of delicate fabrics. I augment this last-named effect by providing the lower corners of the piece 4 with pockets 12, 12 in each of which a weight 13 is disposed.

All the above is accomplished without in any way hooking or pinning the curtain or folding it up.

When the protector is not in use, the clasp 7, 7^a is opened and the protector may be rolled up, as shown in Fig. 2, the dotted line 14 in Fig. 3 indicating the left side of the rolled up device. It is held in this rolled-up condition by closing together the male clasp member 15^a, on the outside thereof, and the female clasp member 15, on the inside. The rolled up protector may be hung from the exposed eyelet 6 upon the hook 8 on the vertical member 9 of the window frame, as shown at the right in Fig. 1, where it will be hidden from view by the curtain hanging naturally with the window closed. The exposed eyelet 6 is placed approximately on the central axial plane of the resulting "cylinder" so that the latter will hang vertically.

If desired, the clasps may be substituted for the eyelets 6, one to snap the protector to the window frame and the other to hold the upper corners of the protector together.

I claim:

1. As a new article of manufacture, a curtain protector comprising a rectangular sheet adapted to be folded about a hanging curtain into an elongated tubular casing open at both ends, fastening means for retaining the sheet in said form, and means for suspending the casing thus formed in a substantially vertical position.

2. A curtain protector comprising a sheet of moisture proof material adapted to be passed about a hanging curtain, and securing means on opposite edges of said sheet for retaining the sheet in a folded position about said curtain.

3. A protector for hanging curtains comprising a sheet of flexible material adapted to be passed about a curtain, securing means

on opposite edges of said sheet for retaining the sheet in a folded position about a curtain and means for suspending the protector.

5. 4. A window curtain protector comprising a quadrilateral piece of flexible material, eyelets for simultaneously supporting

said protector and holding the upper corners thereof together, and clasps for holding the lower corners thereof together.

10

In witness whereof, I hereunto subscribe my name this 21st day of January, 1924.

MARY EDITH WHEELER.
